CLAIM

The ornamental design for an electronic mouse, as shown and described.

DESCRIPTION

FIG. 1 is a top view of an electronic mouse showing the new design;

FIG. 2 is a front view thereof;

FIG. 3 is a back view thereof;

FIG. 4 is a left side view thereof;

FIG. 5 is a right side view thereof; and,

FIG. 6 is a bottom view thereof.

The broken lines shown in the drawings represent portions of the electronic mouse that form no part of the claimed design.
